J. R. Creighton,

Shutter Worker.

No 15,410.

Patented July 29, 1856.

UNITED STATES PATENT OFFICE.

JAMES R. CREIGHTON, OF BOSTON, MASSACHUSETTS.

SHUTTER-OPERATOR.

Specification of Letters Patent No. 15,416, dated July 29, 1856.

To all whom it may concern:

Be it known that I, JAMES R. CREIGHTON, of Boston, county of Suffolk, and State of Massachusetts, have invented certain new and useful Improvements in Window Blind and Shutter Operators and Fasteners; and I do hereby declare the following to be a full, clear, and exact description thereof, reference being had to the annexed drawings, 10 making part of this specification.

The greatest difficulty encountered by the inventor in contrivances for this purpose, is the production of an article at a sufficiently low cost, having the necessary nicety of adjustment, a combination believed to be attained in the present instance, as a good common article of the description herein alluded to can be made at a cost of about 25c. per window.

20 Figure No. 1 is a full size plan of a section of window, constructed and set as usual in brick houses throughout the greater part of the United States. (A) is a part of the inside casing or finish of the window; (B), 25 a horizontal cut through the upright side of the window-frame; (C) is the sash-weight box; (D), the frame-sill of the window, represented as broken, to show the operator (E), (F) is the stone sill; (G), a portion 30 of the brick-work; (H) is part of a window-blind the hinge to which is pivoted at (I).

The exterior of the operator (E) presents a plain cast-iron box or tube, about $5\frac{1}{2}$ inches 35 long, by about $\frac{1}{2}$ of an inch square; it is open at both ends, having at the outer end cast in one piece with it an escutcheon-plate (J) receiving two common screws (K) that secure to operator (E) to the window frame. 40 On the lower edge of the escutcheon-plate (J) is a projection or lip (L) to which is pivoted a bent-arm or lever (M); this arm or lever acts upon the blind or shutter through means of a staple (N) in which it 45 has the required freedom of action, giving motion to the blind or shutter (H) by being pressed alternately upon one or the other side of said staple. On one side of the arm (M) is a projection (O), having on its under side a pivot, by which a shackle (P) 50 is secured to the arm or lever before mentioned; the other end of this shackle is jointed to a slide (Q) the box (E) before mentioned answering as a slide-frame to the 55 same. One of the inner sides of this box (as may be seen in the drawing) is serrated

or toothed (R) and a projection or flange on the slide (Q) passing under said teeth secures the said slide from vertical displacement. On the inner end of the slide (Q) are 60 formed jaws (S. S' S'') these jaws receive (and retain against longitudinal displacement) a serrated tumbler-catch (T T') the vertical displacement of which is prevented by a square extension-rod (U) said rod 65 passing through the jaw (S'') of the slide (in which it has a partial rotary, as well as longitudinal movement,) and through a square orifice (V) in the tumbler-catch (T) (as seen in Fig. No. 2 which is a vertical 70 sectional cut through the operator,) in which orifice said rod is allowed longitudinal motion only. A projection or stud (W) on the under side of the tumbler-catch (T) (as shown in Fig. No. 2) having a limited 75 motion in a transverse slot (X) in the slide (Q) prevents the rotation of the tumbler-catch (T) farther than is necessary to effect the object of locking and unlocking. The parts (S S') of the jaws form guides to the 80 square extension-rod (U) fitting said rod sufficiently close to prevent any rotary motion in the same; by which means it will be seen that the dislodgement of the tumbler-catch (T) is effectually prevented by the entrance of said rod between the guides 85 (S S'). In Fig. No. 1 the dark lines represent the blind as open and folded back against the wall; the red lines representing the same in the reverse position, or shut. 90

Opening the blind, brings the knob or handle (Y) (attached to the extension-rod) into the room; in effecting this operation, the rod (U) has been drawn past the guides (S S') and the end of it which is bent upward, so as to form a lug (Z) has entered a recess in the tumbler-catch (T) designed to receive it, while the partial rotation which was necessary in order to release the tumbler-catch from its previous position (T) 95 has thrown the lug (Z) between said tumbler-catch and the guide (S') thus effecting a connection between the extension-rod and the slide, by which said slide may be moved in either direction and through it the blind, 100 by the bent-arm and connecting shackle as before described. To effect a return of the knob (Y) to its usual position (Y') that it may not continue to project into the room; the first movement required is a partial rotation of said knob, by which the teeth (a) 105 of the tumbler-catch (T') are made to in-

terlock with the teeth (b) in the slide-box; the stop (W) on the tumbler-catch (Fig. No. 2) preventing its rotating farther than is necessary to effect the object of fastening, 5 while at the same time the extension-rod (U) is brought square with the space between the guides (S S') between which it may then be made to slide until the knob (Y) is brought to its place in the window 10 casing. It will thus be seen that when the knob is in the position (Y') the blind or shutter must be securely fastened in whatever position left. The space (c) between the teeth in the box is filled or left flush with 15 the extreme projection of said teeth to prevent fastening the blind in a position in which it would be impracticable to hold it securely in violent winds, however strong the operator or fastener.

20 The square form of operator is sent to the office, as it admits of more ready examination; it is usually provided with a sheet-iron cover to prevent the bent end of the extension-rod (U) from wearing the 25 window-frame-sill, and to exclude such wear from falling in upon the slide.

A better form is shown in Fig. No. 3, in which the top of the box is round, being closed in the casting; flanges (e e) form 30 ways at the bottom for the slide; the space between which affords ample support to the dry-sand-core in casting.

(f) is the serrated surface and (T) the tumbler-catch has its bearings sufficiently 35 removed to one side of the center to allow of the disengagement of the teeth (g) of the tumbler-catch from those in the slide-frame or box (f).

It is desirable for houses already built, 40 that the slide should be on the other side of the arm; to avoid the nails used in the construction of the window frame; in such case the attachment would be made to the bent-arm at (h). There is another advantage 45 attending this point of attachment, as the joints between the arm, shackle and slide are all drawn in, out of the way of being tampered with from the outside, when the blind or shutter is closed, though the appearance 50 when open, is not so desirable as said shackle must protrude.

Fig. No. 4, is a plan of a section of a window, as commonly constructed in wooden houses; it is drawn on a scale of one half 55 the full size. As windows in such houses have but one sill, the form of the bent-arm or lever (i) is necessarily somewhat different, as is also the manner of attaching the same. The dark lines show the position of 60 the blind when open and the red lines show it when shut. The bent arm (i) is pivoted on the frame sill; having bearings in an iron plate (k) secured to the frame sill with common screws; the plate (k) has a circular collar on its upper side perpendicular

with its surface, surrounding the pivot (l) of the arm (i) under said arm; the arm having on its under side a lip, or flange, closing over said collar, the object being to exclude any water that might fall upon the 70 window sill from passing into and under the same. Under the pivot of the arm, is the pivot of a crank (m) which oscillates in a plate (n) said plate being formed by a lateral extension of the slide-box or frame 75 (o) constructed in other respects like the one already described in Fig. No. 1; the shackle (p) being attached to the crank (m) instead of the arm. On the upper side of the crank perpendicular with its center of 80 motion and that of the arm above, is a square tenon about one inch in length, which enters a corresponding socket (r) in the pivot of the arm (i) and thus forms a connection between the slide and the arm. 85 In order to avoid the projection of the arm beyond the front of the house when the blind is closed, a common screw in the bottom of the blind supported by an iron plate (s) is substituted for the staple before 90 mentioned, said screw traversing a slot (v) in the arm of such curve as to allow said arm to fold under the blind or shutter as seen in Fig. No. 4. The square tenon (before mentioned) entering the socket (r) 95 about one inch, allows of such vertical extension between the pivot of the crank (m) and the arm (i) as will adapt them to any ordinary variation in the thickness of window frame sills. The movemnt of the slide 100 (t) and shackle (p) is all within the escutcheon plate (u) as any projection beyond the sill would frequently be much in the way, besides producing an ungainly appearance 105 by such protrusion.

Having thus fully, clearly and exactly described the nature, construction and operation of my improvemnt in window-blind and shutter operators and fasteners, what I claim therein as new and desire to secure 110 by Letters Patent, is—

The attachment of the serrated tumbler-catch (T) to the slide (Q) said catch meshing or interlocking with a similarly serrated or toothed surface—opposed—(R) on the 115 side of the slide-box or frame (E); in combination with the square extension-rod (U) and guides (S S') by which I am enabled to operate the outside blinds or shutters of a house from the inside of the same, and to 120 secure said blinds or shutters in any desired position, without the liability of their dislodgment from the outside, unless by the excise of unusual violence.

In testimony whereof I have hereunto set 125 my hand before two subscribing witnesses.

JAMES R. CREIGHTON.
